STUDIO COUCH

Arthur Wesley, Chicago, Ill., assignor to Burton-Dixie Corporation, Chicago, Ill., a corporation of Delaware

Application February 19, 1938, Serial No. 191,416

5 Claims. (Cl. 5—21)

My present invention concerns features of betterment and advantage in studio-couches and analogous structures, and it relates more particularly to articles of furniture of that type known as high-low, automatic, high-rise constructions, by which is meant that the smaller or lower bed-section of the couch is lifted in operation to the level of the other part of the couch for use as a double bed or possibly as a separate single bed. 10 One primary object of the invention is to provide a simple means for locking the specified under-section of the couch in its elevated operative position and to allow collapse or descent thereof, when it is to be rolled back under the top-section, whereby the structure affords a high elevated surface for the occupancy of the person sleeping on the couch rather than a lower position nearer the floor. 15 A substantial and important feature of the new construction is the locking of such under-section in its raised position beneath the same so as to avoid the use of operable means for this purpose at either end which would take up room and sacrifice length of the mattress of the under-section, and, by having such locking means beneath rather than at the ends, a mattress or cushion can be used almost as long as that of the top-section, notwithstanding the fact that the under section at times must nest under such top 20 or upper section.

A further feature of the invention is that the locking-bars employed act automatically in that the operator merely pulls the spring-balanced, lower couch-section up to operative position and 25 the retention thereof in such elevated position takes place as a matter of course.

Another advantage of this novel construction is that the locking-bars referred to constitute convenient means on which to mount the front 30 panel-board, and, by merely raising the latter slightly by the foot or manually, the unlocking is effected permitting the descent of the movable couch-section and its subsequent backward travel in under the other or upper couch section.

To permit those acquainted with this art to fully understand the present invention, a current, preferred embodiment thereof has been illustrated in the accompanying drawings to which recourse should be made, and, for simplicity, like 35 reference numerals have been employed throughout the several figures of these drawings to designate the same structural elements.

In such drawings:

Figure 1 is a perspective view of the studio-couch in unfolded, double-bed condition;

Figure 2 is a fragmentary plan view of the same on a larger scale with many parts removed or broken away to more clearly show the remaining structural elements;

Figure 3 is a partial perspective view on a still larger scale; and

Figure 4 is an incomplete vertical cross-section on line 4—4 of Figure 3.

By reference to Figure 1, it will be observed that the major, external or upper section of the studio-couch includes end-frames 11, 11, a back 12, an outer frame 13 including a longitudinal bar 14 lengthwise slotted at 15, a spring-unit 16, a combined cushion and mattress 17, and back pillows or cushions 18, 18, the structure being 15 open at the front to accommodate the second, removable, minor or slightly-smaller, inner couch-section as is usual in articles of furniture of this character.

Such second couch-section comprises a rectangular metal frame 21 on which a metal-fabric 22 is yieldingly mounted by means of coiled or helical springs 23, 23 and on this resilient or elastic base, a cushion or mattress 24 of suitable type, such as an inner-spring mattress or cushion, rests, the front of the metal frame 21 having 25 an operating-handle 25.

Frame 21 may be conveniently made of parallel, front and back angle-bars 26, 27 (Figure 3), respectively, each with one of its flanges directed 30 upwardly to assist in maintaining the cushion or mattress 24 in place, each end angle-bar 28 having its ends fastened to the two longitudinal bars and with one flange extended downwardly and lengthwise slotted at 29.

Such frame 21 is supported at each of its opposite ends on a pair of angle-bar crossed-legs 31 and 32 hinged or pivoted together at their middle portions at 33, the upper end of leg 31 being hinged to the corresponding end-bar 28 at 34 and the lower end of the same leg having a roller 35 resting on, and adapted to roll on, the floor, the upper end of the companion leg 32 having a pin 36 slidable in the slot 29 and the lower end of the same leg having a like roller 35 for a comparable purpose.

The lower ends of these two legs 31, at opposite ends of the structure, just above their rollers, are connected together by a bar 37 longitudinally slotted at 38 for a portion of its length, and the corresponding lower portions of the other legs 32 are joined together by an angle-bar 39 having one of its flanges upstanding in a somewhat sloping relation.

Also, the lower end-portions of each pair of 55

crossed-legs 31 and 32 are connected together by a coiled, contractile spring 41, the strength of the two springs substantially balancing the weight of the structure with which they are associated.

In order to maintain a parallel relation between the two, outer and inner, or over and under, sections of the studio-couch, a pair of crossed bars 42 and 43 (Figure 2) are employed, these members being hinged or pivoted together at their crossing point 44, and the bar 42 at one end at 45 is hinged to the bar 31, and, at its other end, it has a pin 46 slidable in slot 15 of the major part of the couch, one end of the other bar 43 being hinged at 46 to bar 44, and, at its other end, it is equipped with a pin 47 slidable in slot 38 of the movable couch-section, but it will be obvious to those acquainted with this art that any other appropriate parallel-motion means could be satisfactorily used.

After the smaller, under section of the couch has been pulled forwardly from beneath its companion, larger, upper section, it may be easily elevated to operative position to bring the top surface of its cushion 24 into substantially the same plane as the upper surface of cushion 11 by a slight lifting effort applied to the handle 25, but, of course, it is necessary to have some appropriate locking-means for holding it in that raised, operative relation, and in the means supplied for such purpose resides one of the important features of the present invention.

For the accomplishment of this result, a bracket 51 is secured to the front face of angle-bar 37 near each end thereof, yet inside of the corresponding crossed-legs 31 and 32, whereby to be out of the way, and hinged at 52 to each such bracket is a locking-bar 53 suitably or appropriately notched at its lower edge at 54 to receive a portion of the other angle-bar 38 in such recess, the forward end portion of the bar being bent at 55 to provide an upright terminal part 56, to the two of which, at opposite ends of the structure, the front panel-board 57 is secured.

To guide these locking-bars in their forward and rearward travels, the upper sloping flange of the angle-bar 38, in register with such locking-bars, may be notched at 58 to receive the bars, and, as a further guiding and retaining means, the bar 38 may be fitted with clips 59 fastened thereto and slotted at 60 in alignment with the recesses 58, whereby, in each instance, the mating and registered slots and notches 58 and 60 form a single recess or opening through which the locking-bar extends and by which it is properly controlled.

From what precedes, it will be clear that the lower-section of the couch may be nested within or under the upper-section, and, when it is desired to convert the structure into a double or single bed, the lower-section is pulled or rolled out forwardly, always parallel to the main-section by reason of the action of the crossed bars 42 and 43, one end of each of which during such operation travels in its confining companion slot.

When such under-section has been fully advanced, its limit of such travel being determined by the pins on the corresponding bars 42 and 43 reaching the inner ends of their slots, it may be raised to the proper height with facility by lifting it by means of handle 25, during which action the two pairs of legs turn on their pivots or hinge-pins at 33 and at the same time the pins 36 travel inwardly in slots 28 and rollers 35 advance on the floor.

As the bar 37 thus moves forwardly with the legs 31 and the bar 38 travels rearwardly with the legs 32, during such elevation of the couch-section, the two locking-bars 53, 53 ride on the metal at the lower edges of the notches 58, this travel of the locking-bars also carrying the front panel 57 with them.

When the notches 54 in the lower edges of the locking-bars 53 coincide with the flange of the connecting-bar 38, these locking-bars drop slightly due to the reception of the flange portion in the notches and the legs are thus securely and automatically fastened against collapse and descent of the now completely and properly elevated couch-section.

The fully-open, locked studio-couch now presents a double-width bed which may be occupied with comfort and safety.

When it is desired to transform such bed into the smaller studio-couch form, the panel is raised slightly by the foot or by the hand engaging its middle portion by means of fabric-loop 18 to release both locking-bars and the couch-section is pushed down, collapsing the crossed-legs and carrying the notches of the locking-bar out of register with the bar 38, and when it has been completely lowered, it may be pushed back under and nested beneath the other section, all as will be readily understood.

Some occupants, such as those, for example, who have breathing difficulty or other physical inconveniences, may desire to have the movable couch section somewhat lengthwise inclined when occupied and this result may be easily accomplished due to the fact that there is sufficient play or flexibility in the various parts or connections whereby, by manipulation of the front panel, only one of the locking bars holds its end of the couch-section elevated, while the other locking-bar is inoperative and its end of the couch-section occupies its lower position.

The manner in which the stated objects and purposes of the invention are accomplished by this novel construction will be easily understood and need not here be repeated.

The invention, as defined by the appended claims, which should be construed as broadly as permitted by the state of the prior art, is not necessarily limited and restricted to the precise and exact details of structure shown and described since these may be modified within reasonable limits without departure from the heart and essence of the invention and without the loss or sacrifice of any of its material benefits and advantages.

I claim:

1. In a studio-couch, the combination of a main open-side couch-section, a companion couch-section adapted to be nested under, or to be slidly withdrawn through said open-side from beneath, said main couch-section without modifying the condition of the latter, said companion couch-section having supporting, elevating and lowering means bearing directly on the floor and constructed to be actuated by the operator to elevate and to wholly support said companion couch-section for use after sliding withdrawal thereof from said main couch-section and to lower the same to allow said companion couch-section to be slid beneath said main couch-section, said supporting, elevating and lowering means including a pair of crossed-legs at each end of the companion couch-section hinged together at their crossing points, a hinge-connection for one of said legs of each pair with said companion couch-

- section, a shiftable connection for the other leg of each pair with said companion couch-section, means to releasably lock each pair of said legs against turning on their crossing-point hinges, whereby to maintain said companion couch-section in its operative elevated position, said two locking-means being located beneath and within the length covered by said companion couch-section, and a longitudinal panel of the studio-couch accessible to, and operable by, the operator and connected to both of said locking-means to effect their simultaneous release.
2. The studio-couch presented in claim 1 in which said open-side of the studio-couch is the front-side thereof and in which said panel is the front panel of the studio-couch.
3. In a studio-couch, the combination of an open-front main couch-section, a companion couch-section adapted to be nested under, or to be slidly withdrawn through said open-front from beneath, said main couch-section without modifying the condition of the latter, said companion couch-section having supporting, elevating and lowering means bearing directly on the floor and constructed to be manually operated to elevate and to wholly support said companion couch-section for use after sliding withdrawal thereof from said main couch-section and to lower the same to allow the companion couch-section to be slid beneath said main couch-section, said supporting, elevating and lowering means including a pair of crossed-legs at each end of the companion couch-section hinged together at their crossing points, a hinge-connection for one of said legs of each pair with said companion couch-section, and a shiftable connection for the other leg of each pair with said companion couch-section, a forwardly-extended lock-bar for each end of said companion couch-section, said lock-bars being beneath and within the length of said companion couch-section, means hingedly connecting said lock-bars to the lower portions of corresponding back legs of said pairs, means to lock said bars releasably to the lower portions of the front legs of said pairs to prevent descent of the elevated companion couch-section, and a front panel of the studio-couch connecting said lock-bars together and engageable by the operator to effect the simultaneous release of said lock-bars preliminary to descent of the companion couch-section and its return under the main couch-section.
4. The studio-couch set forth in claim 3, including in the combination, a member connecting together the downwardly-rearwardly inclined legs of the two ends, an element connecting together the downwardly-forwardly inclined legs of the two ends, and in which studio-couch said lock-bars are hinged to said member and constructed to releasably lockingly engage said element.
5. In a studio-couch, the combination of an open-front main couch-section, a companion couch-section adapted to be nested under, or to be slidly withdrawn through said open-front from beneath, said main couch-section, without modifying the condition of the latter, said companion couch-section having supporting, elevating and lowering means bearing directly on the floor and constructed to be manually operated to elevate and to wholly support said companion couch-section for use after sliding withdrawal thereof from said main couch-section and to lower the same to allow the companion couch-section to be slid beneath said main couch-section, said supporting, elevating and lowering means including a pair of crossed-legs at each end of the companion couch-section hinged together at their crossing points, a hinge-connection for one of said legs of each pair with said companion couch-section and a shiftable connection for the other leg of each pair with said companion couch-section, means to releasably lock each pair of said legs against turning on their crossing-point hinges, whereby to maintain said companion couch-section releasably in its operative elevated position, and a front-panel of the studio-couch, accessible to, and operable by, the operator and connected to both of said locking-means to effect their simultaneous release preliminary to descent of the companion couch-section and its return under the main couch-section through the open-front of the latter.

ARTHUR WESLEY.
